UNITED STATES PATENT OFFICE.

JOHN L. WILLIAMS, OF PHILADELPHIA, PENNSYLVANIA.

ICE-TONGS.

No. 884,448.

Specification of Letters Patent.

Patented April 14, 1908.

Application filed December 14, 1907. Serial No. 406,473.

To all whom it may concern:

Be it known that I, JOHN L. WILLIAMS, a citizen of the United States, residing at Philadelphia, in the county of Philadelphia and State of Pennsylvania, have invented 5 certain new and useful Improvements in Ice-Tongs, of which the following is a specification.

My invention relates to that class of ice 10 tongs formed from a single length of wire.

The object of my invention is to form an ice tongs of a single length of wire comprising, a handle bar formed by coiling the wire in close coils, springs at the ends of the handle 15 formed by coiling the wire in a plane at right angles to the handle coils, and arms extending downwardly and inwardly from the springs and terminating in penetrating prongs. This object I accomplish by the 20 construction shown in the accompanying drawing in which the figure is a side elevation of my improved ice tongs.

A, designates the handle bar formed by coiling a length of spring wire, at its middle 25 portion, into a series of close or tight coils *a* so as to form a practically rigid bar. The wire at the ends of this handle bar A is coiled at right angles to the coils *a*, to form the

springs *a'*, and the ends of the wire extend downwardly and inwardly from the springs 30 *a'* to form the arms *a*² which terminate at their ends in penetrating points *a*³ in the plane of the handle bar A⁷ and at a point intermediate the ends thereof.

It will be seen that the tight coils *a* form a 35 strong and practically rigid handle and that they also hold the springs *a'* pressed firmly towards each other to thus afford extra gripping action to the tongs. The springs *a'* press the gripping arms *a*² and their points *a*³ 40 together with sufficient force to cause a block of ice to be firmly and securely gripped.

What I claim is:—

An ice tongs formed of a single length of wire and comprising a tightly coiled handle 45 bar, coiled springs at the ends of the bar and at right angles thereto, and arms extending from said springs downwardly and inwardly below the handle bar and terminating in 50 penetrating points.

In testimony whereof I affix my signature, in presence of two witnesses.

JOHN L. WILLIAMS.
